(57) **CLAIM**

The ornamental design for a lamp, as shown and described.

DESCRIPTION

FIG. 1 is a perspective view of a lamp showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is an enlarged portion view labeled, "FIG. 9," shown in FIG. 1; and,

FIG. 10 is an enlarged portion view labeled, "FIG. 10," shown in FIG. 2.

The even broken lines in the drawings depict portions of the lamp that form no part of the claimed design. The dash-dot lines define the boundary of the enlarged portion views shown in FIGS. 1, 2, 9 and 10.
